Primary Examiner — Angela J Lee*(74) Attorney, Agent, or Firm* — Harness, Dickey & Pierce(57) CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing my new design; and,

FIG. 2 is a front view of a display screen or portion thereof with icon showing an alternative embodiment of the new design.

The broken lines shown in the drawings represent portions of the display screen or portion thereof that form no part of the claimed design.
